(57) **CLAIM**

The ornamental design for a display screen or portion thereof with a graphical user interface, as shown and described.

DESCRIPTION

FIG. 1 is a front view of a display screen or portion thereof with a graphical user interface, showing our new design, according to a first embodiment thereof; and,

FIG. 2 is a front view of a display screen or portion thereof with a graphical user interface, showing our new design, according to a second embodiment thereof.

The broken lines illustrate the display screen or portion thereof, and the broken lines form no part of the claimed design.

1 Claim, 2 Drawing Sheets

FIG. 1

FIG. 2
